UNITED STATES PATENT OFFICE.

EDMUND M. PITTS, OF FRESNO, CALIFORNIA, ASSIGNOR TO SUNLAND SALES COOPERATIVE ASSOCIATION, OF FRESNO, CALIFORNIA, A CORPORATION OF CALIFORNIA.

FOLDING BOX.

Application filed October 4, 1926. Serial No. 139,312.

This invention relates to folding pasteboard boxes in general, and in particular to such a box adapted for packing therein of commodities in unit quantities as pounds, 5 dozens, gross, etc., for delivery to the retailer, and which box also provides for advantageous display of the goods by the retailer and for direct sale of the goods therefrom.

10 The principal objects of the invention are to provide an improved layout of blank so that the box may be folded from a single piece of cardboard or heavy paper, and which when folded will form a more durable 15 and better reinforced box than heretofore made, which will provide for necessary advertising matter or description of the goods being displayed, all on one side of the sheet only, will maintain a more attractive package as the goods are sold therefrom when the box is only partly filled, and will be more rugged when arranged in slanted display 20 position.

These and other objects are achieved in 25 the folding paper box construction shown in the accompanying drawing in which:

Fig. 1 is a plan of the scored paper or cardboard blank.

Fig. 2 is a perspective view of the box 30 folded therefrom.

Fig. 3 is a perspective view of the box as arranged to display the commodity for sale.

Fig. 4 shows the blank partly folded into 35 box form.

In the blank shown in Fig. 1 the dot and dash lines denote scored or creased lines adjacent which the sheet is to be bent away from the observer thus V while the plain 40 dotted lines represent scorings where the sheet is to be bent in the reverse direction thus A, in forming the box.

The various sections and features of the blank are lettered and numbered A, B, C, 45 etc., and 1, 2, 3, etc., and since this lettering and numbering is carried out in the partial and folded views it is thought will be sufficient disclosure as to the manner of folding without entering several pages of 50 additional instructions herein which would be entirely superfluous to anyone skilled in the art.

When the box is all folded ready for shipment it appears as in Fig. 2 with ends of

side flaps R—S, T—U of lid Q—P, engaged 55 in cuts 1—2 of the sides C—B. The ends of the box are of several thicknesses. The flap H of the left hand end is hooked under the part 4 inside of the box, and the notch 8 hooked under the part 5.

The lid of the box opens by bending on the various scored lines to lie under the box as shown in Fig. 3, and when so opened supports the box on a table or counter at an angle for display of its contents as indicated. 65 The box when thus opened reveals but a portion of its interior since the section D overlies the upper part. This part D acts as a shield as the goods are sold from the box, so that the goods falling or being moved 70 to the lower end always makes the box seem relatively full as the empty portion is covered by the shield. The shield also serves for printing instructions or advertising matter relative to the goods, and an additional 75 tab is provided at D' to receive the trademark imprint, name of the manufacturer, or other pertinent data, and owing to the angle this tab immediately attracts the attention of a person viewing the display. 80

By my construction the lower end F being of several thicknesses of card held in place by the part 4 as explained will not warp or sag out of shape, and the supporting portions R and T are each provided with an inwardly folded leg as at S and U thereby preventing their supporting edges from warping due to the weight of the goods upon them, and the sections R, T are tied by members X and Y overlapping V and W all 90 held in place by Z locked under 7.

Also it should be observed that the package as arranged for display is stable and may be moved around as a unit since the supporting portions are locked to the bottom A of the box by means of the portion 95 6 engaged through the cut 3.

Attention is called to the slight widening of the blank at the ends of the lines separating X from Z, also N from O, and H from G, as indicated on Fig. 1 of the drawing. This feature insures the respective portions so widened wedging tightly in place when folding the blank into box form so that they remain in position and are not easily displaced.

Another point is that with my construction any printing to appear on outer sur-

faces of the folded box or on D and D' of the open box, is all done on one side only of the flat blank.

I claim:

- 5 1. A folding box of the character described provided with a lid section hinged to the same adapted for swinging from a position covering the box to a position underneath a portion only of the same for propping the box at an angle on a supporting surface, said lid section being provided with a pair of side flaps for so supporting the box each provided with an inwardly turned extension lying on the supporting surface.
- 10 15. 2. A folding box of the character described provided with a lid section hinged to the same adapted for swinging from a position covering the box to a position underneath

the same for propping the box at an angle, the box when so uncovered being provided with a closed and locked sub-cover concealing some of the interior of the box from view.

3. A folding box of the character described provided with a lid section hinged to the same adapted for swinging from a position covering the box to a position underneath the same for propping the box at an angle, said box when so uncovered and supported being provided with a closed sub-cover concealing portion only of the interior of the box from view and said sub-cover provided with an exposed flap at its upper end adapted to project upward from the box.

EDMUND M. PITTS.
